UNITED STATES PATENT OFFICE.

JOHN A. HAYS, OF PITTSBURG, PENNSYLVANIA.

FOLDING BOX.

SPECIFICATION forming part of Letters Patent No. 594,690, dated November 30, 1897.

Application filed January 21, 1897. Serial No. 620,137. (No model.)

To all whom it may concern:

Be it known that I, JOHN A. HAYS, a citizen of the United States of America, residing at Pittsburgh, in the county of Allegheny and State of Pennsylvania, have invented certain new and useful Improvements in Folding Crates, of which the following is a specification, reference being had therein to the accompanying drawings.

10 This invention relates to certain new and useful improvements in folding crates, and has for its object to construct a crate of the above description that may be advantageously employed for shipping eggs, fruit, or 15 may be employed for shipping poultry and the like.

The invention further aims to construct a crate that when folded will occupy less than one-third of the space when in the built-up 20 form, and thus save considerably in the freight in returning the empty crates.

A still further object is to construct a crate that will be extremely simple in its construction, strong, durable, effectual in its operation, and comparatively inexpensive to manufacture.

With the above and other objects in view the invention finally consists in the novel construction, combination, and arrangement of 30 parts to be hereinafter more specifically described, and particularly pointed out in the claim.

In describing the invention in detail reference is had to the accompanying drawings, 35 forming a part of this specification, and wherein like letters of reference indicate similar parts throughout the several views, in which—

Figure 1 is a perspective view of my improved folding box with the lid open. Fig. 40 2 is a view of the box when in the folded position. Fig. 3 is a perspective view of a portion of one of the sides and a portion of the partition, showing manner in which the partition is secured in position.

45 Referring now to the drawings by reference letters, *a* indicates the rear side piece, *b* the front side, and *d* and *e* the respective ends, said side and end pieces being secured together by hinges *ff*, said hinges at two of the 50 corners being on the outside of the end and side pieces, and at the opposite corners the said hinges being placed in the same relative positions, on the inner face of the side

and end pieces. A bottom *g* is secured by hinges *h h* to the front side *b*, said bottom 55 having secured thereto by hinges *kk* the partition *l*, which is provided on its upper face with keepers *m m*, in which is journaled a rod *n*, provided on its one end with a knob *o*, while the opposite end is adapted to engage 60 in the rear side piece *a* and lock the box in the built-up form. Hinged to the back *a* is a top or lid *p*, carrying a hasp *q*, adapted to engage a staple *r* in the front *b*.

The manner in which the box is folded is 65 as follows: The rod *n* is released from its engagement with the rear side piece *a*, which will permit the partition to fold onto the bottom *g*, and also permit the said bottom *g* to swing on its hinges, bringing the same out of 70 the way of the end and side pieces, which will then fold endwise in either direction by reason of the arrangement of the hinges *ff*. For convenience in handing I have provided strips *s s* on the ends, which serve as grips, and secured on the base *g* is a stop *t*, against which the end abuts and serves to strengthen the 75 box.

It will be noticed that various changes may be made in the details of construction without departing from the general spirit of my construction.

Having fully described my invention, what I claim as new, and desire to secure by Letters Patent, is—

85 In a folding box, the combination of the side and end pieces hinged together in such a manner as to swing endwise in folding, a bottom hinged to the front, a lid hinged to the back, a partition hinged to the bottom and 90 provided with a cut-away portion and a semi-circular slot in a plane above the same, a locking-rod carried by said slot and secured to the same by staples and provided with a head, a lug on the bottom to engage one of 95 the ends and hold the box rigid, and a hasp and staple for fastening the box when in the built-up form, substantially as shown and described.

100 In testimony whereof I affix my signature in presence of two witnesses.

JOHN A. HAYS.
